TO F. X. HOOPER COMPANY, OF GLENARM, MARYLAND, A CORPORATION OF MARY-
LAND.

SET-UP BAR FOR SLOTTING AND CREEASING MACHINES.

Application filed May 7, 1924. Serial No. 711,645.

This invention relates to an attachment for cardboard slotting, creasing and cutting machines, for facilitating the adjustment of the slotting, creasing and cutting heads to operate along exact lines on the cardboard. In setting the heads by the usual methods to make a box-blank of one form, the machine must be stopped for a considerable time while the operator, leaning over the machine, adjusts the heads independently, usually by a foot rule or scale. The slotting wheels or heads on one pair of shafts must be set in a certain relation to the scoring heads on another pair of shafts and the trimming heads, for trimming the edges of the blanks, must be independently adjusted on one of the pairs of shafts. When it is desired to make a different blank, some or all of the heads must be again adjusted independently by the rule or scale.

The attachment of our invention comprises a set-up bar, adapted to fit into suitable open bearings in the frame of the machine, so that it can be readily removed and replaced, and having a scale and index members, the latter adjustable along the bar and adapted to be set by reference to the scale for positioning the slotting, creasing and cutting heads of the machine. To set the index members, the bar may be removed from the machine and placed on a suitable support, and the index members can then be set with greater facility than if the bar were in the machine. After the members have been set to their proper positions, the bar is placed in its bearings in the machine, and lies parallel with the shafts which carry the slotting, creasing and trimming heads. The index members comprise hubs which can be clamped to the bar at any point and arms or fingers which project toward the slotting, creasing and cutting heads on the adjacent shafts. These heads can then be quickly adjusted to correspond with the positions of the index arms, and the bar may then be removed from the machine. While the machine is operating to cut blanks of one kind or size, an operator can set the index members on the bar for positioning the heads to operate on blanks of another kind or size. Thus, a large saving in the operating time of the machine is effected.

In the accompanying drawing,

Fig. 1 is a top plan view of a machine for

slotting, creasing and trimming box blanks, 55 showing the set-up bar mounted in the machine;

Fig. 2 is a plan view of the set-up bar, in the position shown in Fig. 1, on a larger scale and partly broken away, with some of the index members thereon;

Fig. 3 is a side view of the bar, partly broken away, on the same scale as Fig. 2; and,

Fig. 4 is an enlarged perspective view of a portion of the bar and one of the index 65 members.

Referring to the drawing, *a* represents, in part, a machine for slotting, creasing and trimming the box-blanks, and *b* represents the set-up bar which is shown mounted in 70 the machine in Fig. 1. 1 indicates a shaft carrying slotting heads 2, each head being provided with a slotting knife 3, and it will be understood that these slotting knives co-operate with grooved heads on the corresponding shaft located below the shaft 1, as usual, the lower shaft not being shown in the drawing. Creaser heads 4, and heads 5, carrying trimming knives 6, are mounted upon a shaft 7, and it will be understood that 75 co-operating heads are mounted upon a shaft below the shaft 7, but not shown in the drawing. The blanks which are to be cut and creased are fed into the machine from a feed table 8 and are carried through the machine by pull rollers 9, upon shafts 10 and 11, co-operating with pull rollers on similar shafts, not shown. The machine frame is provided with open bearings 12, at its ends, adapted to receive the ends of the set-up bar. 80

The end or bearing portions 13 of the bar which fit in these bearings, are cylindrical and of smaller diameter than the body of the bar, and shoulders 14, constituting stops, are thus formed on the bar and adapted to fit 85 closely against the ends of the bearings 12, so as to prevent endwise movement of the bar when it is in the machine. The bar is formed with a shallow groove 15, extending from end to end of its body portion, and within this groove is arranged a tape 16, having graduation marks reading from the center of the tape in opposite directions and indicating small fractions of an inch, as sixteenths. The bar is also flattened adjacent 100 the scale, as shown at 17. Index members *c* and *d* are mounted upon the bar, each index member comprising a hub 18 and a clamping

screw 19 which extends through a threaded opening in the hub and is adapted to bear against the flattened part 17 of the bar to clamp the hub in any desired position of adjustment with respect to the scale. The hubs *c* are provided with two radially projecting arms 20 and 21, and the hubs *d* are each provided with a radially projecting arm 22. The sides 20^a and 21^a of the arms 20 and 21 are flush with one end *c'* of the hub from which they project, and the ends of the arms 21 are cut away on their opposite sides, as shown at 21^b, to reduce the extremities of these latter arms to one half the thickness 15 of the slotting knives. The sides 22^a of the arms 22 are flush with the ends *d'* of the hubs *d*.

When the bar is placed in the machine, as shown in Fig. 1, the arms or fingers 21 on 20 the hub *c* will project toward the slotting heads on the shaft 1 and the arm 20 will project toward the creasing heads on the shaft 7 and the arms or fingers 22 on the hubs *d* will project toward the trimming heads 5. 25

In using the bar, the operator, with the bar removed from the machine, will space the index members *c*, by reference to the scale, so that the distance between their faces *c'* will correspond with the distance between the center lines of the slots to be cut in the blanks, and will space the index members *d* so that the distance between their faces *d'* will be equal to the width of the blank, and 30 will then clamp the index members to the bar. The bar will then be placed in the open bearings 12 and the operator will move the slotting heads into position to aline the sides of the slotting knives with the cut-away sides 21^b of the arms 21, when the sides 21^a will lie in the central planes of the knives. The creasing heads will be moved to 35 aline central score marks 4^a thereon with the flat sides 20^a of the arms 20, and the heads 5, carrying the trimming knives 6, will be adjusted by reference to sides 22^a of the arms 22 to set the knives to trim the blanks to the proper width. After the various heads have been adjusted upon the 40 shafts, the set-up bar may be removed, and, while the machine is in operation, an operator may adjust the index members on the set-up bar for setting the heads to different 45 positions to form box-blanks of a different width or having differently spaced slots and creases. It will be evident that by the use of this bar, the operating time of the machine may be increased and the operator will be 50 saved considerable time and labor in adjusting the various heads.

What we claim is:

1. In a machine of the class described, the combination with a frame having a shaft and members thereon for operating on the 55 cardboard, said members being adjustable

along the shaft, of a set-up bar having a scale thereon, bearings on the machine for detachably holding said bar parallel with said shaft and for preventing endwise movement of the bar, and index members adjustable along the bar for positioning the first mentioned members on the shaft. 70

2. In a machine of the class described, the combination with a frame having a shaft and members thereon for operating on the 75 cardboard, said members being adjustable along the shaft, of a set-up bar having a scale thereon, bearings on the machine for detachably holding said bar parallel with said shaft and for preventing endwise movement of the bar, said bearings being open to permit of the ready removal and insertion of the bar, and index members adjustable along the bar for positioning the first mentioned members on the shaft. 80

3. In a machine of the class described, the combination with a frame having a shaft and members thereon for operating on the cardboard, said members being adjustable along the shaft, of a set-up bar having a 85 scale thereon, bearings on the machine for detachably holding said bar parallel with said shaft, said bar having a part, forming a stop, adapted to engage a stationary part on the machine to prevent endwise movement of the bar, and index members adjustable along the bar for positioning the members on the shaft. 90

4. In a machine of the class described, the combination with a frame having a shaft and members thereon for operating on the 95 cardboard, said members being adjustable along the shaft, of a set-up bar having a scale thereon, bearings on the machine for detachably holding said bar parallel with said shaft, said bar having shoulders adapted to engage the ends of the bearings to prevent endwise movement of the bar, and index members adjustable along the bar for 100 positioning the first-mentioned members on the shaft. 105

5. In a machine of the class described, the combination with a frame having parallel shafts and rotary heads on each of said shafts, said heads being adjustable along the 115 shafts, and said frame having open bearings on a line parallel with the shafts, of a set-up bar having a scale and having parts adapted to fit in said bearings and shoulders adapted to engage stationary parts of the 120 machine to prevent endwise movement of the bar, and index members adjustable along the bar, each index member having parts adapted to project toward the heads on both 125 of said shafts when the bar is in said bearings.

In testimony whereof we hereunto affix our signatures.

ELLWOOD A. METZ.
THOS. S. FITCHETT.
